UNITED STATES PATENT OFFICE.

DAVID L. HARDY AND ALFRED L. MAPLE, OF INDIANAPOLIS, INDIANA,
ASSIGNORS TO WEBSTER P. BUSHNELL, OF MONTICELLO, INDIANA.

LETTER-PRESS.

SPECIFICATION forming part of Letters Patent No. 628,266, dated July 4, 1899.

Application filed April 18, 1898. Serial No. 678,093. (No model.)

To all whom it may concern:

Be it known that we, DAVID L. HARDY and ALFRED L. MAPLE, of Indianapolis, county of Marion, and State of Indiana, have invented 5 a certain new and useful Letter-Press; and we do hereby declare that the following is a full, clear, and exact description thereof, reference being had to the accompanying drawings, in which like figures refer to like parts.

10 Our invention has for its object an arrangement or construction whereby the moistening-cloth while the copy is being made will be subjected to the same pressure, no more and no less, that it is subjected to while in the bath.

15 The result of this is that no water will be forced out of the moistening-cloth while a copy is being made, and hence neither the copy nor the original writing will be in any manner blurred or marred by reason of too much 20 moisture. With this arrangement the sheet in the copy-book on which the copy is made receives its moisture evenly from the moistening-cloth by absorption only. The function of the press is merely to bring all parts of the 25 moistening-cloth in contact with the copying sheet. No additional pressure is required. If there should be additional pressure, as is the case with most presses of which we are aware, water will be forced out of the moistening-cloth and the ink will be caused to run.

In carrying out this invention we provide that the volume of matter under the press shall be identically the same when the moistening-cloth is being pressed out just before the 30 copy is made as when the copy is being made, so the same pressure will be brought upon the moistening-cloth in the tank and in the copy-book. To effect this last result, a stop is provided that limits the operation of the press 35 and the degree of pressure when the copy is being made to the same position and the same degree as when the moistening-cloth is being pressed out for use in the copy-book.

Another feature of our invention relates to 40 a bath-tank so constructed that it can be used and placed beneath the copy-book during the copying and at all other times, so that the amount of matter upon which the press acts will always be identical. To carry out this 45 idea, we fill the bath-tank with a wooden block or similar absorbent block that is solid enough

to resist the pressure of the press and is absorbent enough to hold the moisture in the tank. In order to preserve the moisture in the tank, we make the same also air-tight. This 55 and the other features of our invention will more fully appear from the accompanying drawings and the following description and claims.

In the drawings, Figure I is a vertical central longitudinal section of our letter-press. Fig. II is a central horizontal section of one of the stop-nuts. Fig. III is a central vertical longitudinal section of the bath-tank.

A very old-style type of letter-press is here 60 shown, whose description it is needless here to present. We provide on the screw 1 stop-nuts 2 and 3 to limit the downward movement of the press and adjust it. Our invention is not necessarily limited to the use of the stop-nuts on the kind of press shown, but what is shown is merely to explain the general nature of this feature of our invention.

Our invention embraces the use of a stop upon the press whether it be in the form shown 65 or any other form. As seen in Fig. II, these stop-nuts may be made in halves, with flanges clamped by the screws 4, so that they can be conveniently and quickly added to the old style of press, as is shown herein.

Under the press shown in Fig. I there is to be seen a copy-book 5 and a bath-tank 6. The bath-tank is below and the copy-book above, this being the most convenient position. Both should be left under the press while copying 75 and at all other times. The bath-tank furnishes a support for the book, and the two furnish a stable and unchanging volume of matter upon which the press acts.

The bath 6 comprises a metallic tank provided with a lid 7 and a rubber cushion 8, secured within the angle of the lid all the way around. The sides of the tank are turned in to form the flange or seat 9, upon which the rubber cushion 8 rests. This flange or seat 95 is sloped downward and inward to cause the water or moisture to run inward. When pressure is exerted on the press, and thereby upon the lid 7, it is obvious that the tank is rendered air-tight, and this is its proper condition, excepting when it is opened to remove or replace a moistening-cloth. Within the 100

tank a wooden block 10 is shown, formed of two boards secured together, with their grain running at right angles to each other. This board 10 has three functions. In the first 5 place the moistening-cloths 11 are laid upon it in any desired number. They are thereby kept straight and in place. In the second place the block 10 absorbs and distributes the moisture in the tank and conveys it to the 10 cloths upon it. In the third place it furnishes a solid foundation or rest for the book under the action of the press. Along the under side the wooden block is provided with a series of grooves 12, whose function is to aid in the 15 distribution of the water in the lower part of the tank to the various parts of the block. It is immaterial whether the passage-ways for this distribution of the water are effected by means of grooves in the block or in the bottom 20 of the tank. The flange 9 should extend almost to the block to hold it in place and yet be far enough away from it not to interfere with the expansion of the block when charged with water.

25 In the operation of this press it is immaterial what degree of pressure is exerted, as that may be such as will suit the particular operator. The same results follow, whether the pressure is great or small, so long as the pressure 30 is being taken is the same as the pressure on it just before it is taken from the bath. Hence it is also immaterial how much water there may be in the tank, provided there is enough 35 to moisten the cloths. Too much water in the tank or in the cloth can do no harm and is immaterial, and in this lies the chief feature of our invention.

In presses heretofore, so far as we are 40 aware, there has been no means to regulate the pressure, so that the same pressure is exerted on the cloth before it is put in the copy-book and on it while the copy is being made. The degree of pressure in such presses is varied 45 according to the strength of the individual or the accidental and varying application of strength on the press. In fact, it is quite common to subject the cloth before use to no pressure. It is also common to run the cloth 50 through a wringer where the pressure has no relation to the pressure subsequently exerted by the press in making the copy. The result has been with nearly every letter or paper copied the ink in portions of it has been made 55 to run and a smooth uniform copy has been largely accidental. These objections are overcome by this invention.

In use the screw or press is turned down as tight as the operator desires. Then the lock-

60 nuts are turned down snugly into place, as shown in Fig. I. Then the press is released, the copy-book taken out, the bath-lid lifted, and any desired number of moistening-cloths removed from the bath and put in the book in the ordinary way. Then the press is turned 65 down until stopped by the lock-nut. This operation not only accomplishes the desired objects above specified, but it is easy to operate, as there is no reason for the operator to strain herself, for the press determines for 70 her the degree of pressure required. It is immaterial in such cases whether the pressure exerted by the press is great or small, as in either case the action of the press on the moistening-cloth will be the same.

Enough space should be left in the tank about the wooden block to receive the surplusage of water when it is first put in and before it is taken up by the block.

What we claim as our invention, and desire 80 to secure by Letters Patent, is—

1. A letter-press including means for pressing out the cloth or other moistening-pad in the bath-tank by the pressure of the press, and a stop for adjusting and limiting the action 85 of the press.

2. A letter-press including a bath-tank adapted to be placed in the press with the copy-book, means therein for subjecting the moistening cloths or pads to the pressure of 90 the press, and a stop for adjusting and limiting the action of the press.

3. A letter-press including a press, a bath-tank with a lid depressible by such press, and means within the tank for holding the moistened cloths or pads in engagement with the lid in the press.

4. In a letter-press a bath-tank whose sides are inwardly turned to form a seat or flange, a cushion secured on the under side of the 100 lid of the tank to rest upon said flange.

5. A letter-press including a bath-tank adapted to be placed with the copy-book under the press and having within it a wooden block whose upper surface is adapted to receive the moistening cloths or pads, a lid for such tank adapted when subjected to pressure to press upon such cloths or pads, and a stop for adjusting and limiting the action 105 of the press.

In witness whereof we have hereunto affixed our signatures in the presence of the witnesses herein named.

DAVID L. HARDY.
ALFRED L. MAPLE.
